UNITED STATES PATENT OFFICE.

ALBERT D. JUDD, OF NEW HAVEN, CONNECTICUT.

IMPROVEMENT IN REVERSIBLE LATCHES.

Specification forming part of Letters Patent No. 124,960, dated March 26, 1872.

To all whom it may concern:

Be it known that I, ALBERT D. JUDD, of New Haven, in the county of New Haven and State of Connecticut, have invented a new Improvement in Reversible Latches; and I do hereby declare the following, when taken in connection with the accompanying drawing and the letters of reference marked thereon, to be a full, clear, and exact description of the same, and which said drawing constitutes part of this specification, and represents, in—

Figure 1, a side view; Fig. 2, the same, with the side of the case removed; and in Fig. 3, the same, illustrating the manner of reversing.

This invention relates to an improvement in that class of reversible latches commonly called stove-door latches—that is to say, a latch in which the bolt is drawn by a thumb-lever; and the invention consists in the combination of the latch-bolt and a lever and connecting-rod to connect the said lever to the said bolt, the said connection being pivoted to the said lever between the fulcrum and the other end, the said fulcrum being nearly in a line parallel to the path of the pivot which connects the rod to the tail of the bolt.

A is the case; B, the face-plate; C, the latch-bolt head; D, the tail of the latch-bolt, resting in the case between the two studs or guides a, with a spring arranged to bear against the bolt-head, the tendency of which is to force the bolt outward. On the tail of the bolt an arm, E, is arranged, from which a connecting-rod, F, extends to a lever, G H, the said lever

pivoted at b. Through the case a screw, d, is passed to secure the case together, and this screw passes forward of and in such relative position to the arm E or other projection on the tail of the bolt that, when inserted, as in Fig. 2, it will prevent the bolt-head from being thrown forward through the face-plate only to the extent required for use; but when the said screw is removed, then the bolt will be thrown forward outside the face-plate, as seen in Fig. 3, in which position (being attached to the head E so as to turn freely therein) the bolt-head may be reversed, or set for a right or left-hand door.

The thumb-lever of the latch-handle passes through the door below the arm H of the lever, so that when the thumb-lever is raised it raises the lever G H, as denoted in broken lines, Fig. 2, drawing in the bolt, as also denoted in broken lines.

I claim as my invention—

The combination of the latch-bolt C D and the lever G H and the connecting-rod F, when the said connection F is pivoted to the lever between the fulcrum and the other end of the lever, the said fulcrum in a line nearly parallel to the path traversed by the pivot which connects the rod to the tail of the bolt, substantially in the manner and for the purpose specified.

ALBERT D. JUDD.
